RECEIVING SYSTEM

Charles M. Burrill, Haddonfield, N. J., assignor to
 Radio Corporation of America, a corporation of
 Delaware

Application November 30, 1938, Serial No. 243,107

3 Claims. (Cl. 250—20)

This invention relates to radio receiving systems and, more particularly, to a method of and means for reducing fading which is caused by the simultaneous reception of ground and sky waves.

Among the objects of this invention are the provision of means for improving radio reception; the provision of means for reducing ground wave reception in order to provide uninterrupted sky wave reception; the provision of a method for adjusting and utilizing a directive antenna for the reduction of fading; and the provision of a method of receiving radio signals, without disturbances due to selective fading, by eliminating the constant ground wave component of the received signal by an adjustment made in the absence of a sky wave and then utilizing the sky wave for reception.

One well known system of providing uninterrupted reception of radio signals is the so-called "diversity" system, in which a plurality of widely separated antennas are provided and connections are automatically made to the one delivering the greatest signal amplitude at any time. This system is satisfactory when there is no cost or space limitation. However, it is not practical for general use because of the expense of the number of antennas which are required, and because a large land area is usually not available. In accordance with my invention, a system of reception is provided which accomplishes the results of diversity reception with the expenditure of but little more than is required for the usual broadcast antenna.

In practicing my invention, two antennas may be employed but preferably one antenna is used which may, by a simple switching system, be converted from a directional to a non-directional antenna. In accordance with this system, the "diversity" resides not in the multiplicity of points of reception, but rather in the directional characteristic of the antenna. Consequently, my system is particularly advantageous for use with home receivers in regions where selective fading or interference from man-made interference is troublesome.

It is well known that the major cause of selective fading is interference between the ground wave and the corresponding sky wave which is reflected from the ionosphere. The interference may be reduced by eliminating either the sky wave or the ground wave. This has been recognized by earlier inventors, but, in every instance, the problem of reducing fading has been attacked by providing means for reducing the sky wave. I have found, however, that neither

the direction nor the intensity of the sky wave is constant. The sky wave changes from day to day and even from hour to hour. Consequently, any device which is adjusted to selectively eliminate the sky wave requires constant readjustments. To obviate this disadvantage, I propose to balance out the ground wave, since the propagation of the ground wave is steady and reliable. Having eliminated the ground wave, and having an antenna receptive only to the sky wave from a particular transmitter, changes in the angle and polarization of the sky wave affect only the intensity of the received signal which may readily be controlled in the usual manner by an automatic volume control.

It is also well known that selective fading due to sky wave interference is noticeable mainly during the hours of darkness. Daytime reception, especially from local stations, is usually free from selective fading. I, therefore, propose to utilize the ground wave signal whenever conditions are such that its reception is possible without interference from the sky wave, by providing a separate vertical antenna for use during the daytime, or by providing a switch which will convert the sky wave antenna into a ground wave antenna.

This invention will be better understood from the following description when considered in connection with the accompanying drawing. Its scope is indicated by the appended claims.

Referring to the drawing,

Figure 1 is a schematic illustration of an embodiment of my invention utilizing a loop antenna;

Figure 2 is a schematic illustration of an alternative embodiment of my invention utilizing a dipole antenna; and

Figure 3 is another embodiment utilizing a horizontal loop and a separate ground wave antenna.

Referring to Fig. 1, a loop antenna 3 is connected through a transmission line 5 and a coupling transformer 7 to a receiver 9. The loop antenna 3 is adjustably mounted so as to be rotatable about its horizontal and vertical axes.

In order to explain the directive operation of such an antenna, I have shown a transmitter 11 radiating waves which travel to the receiving loop directly and also after reflection from the ionosphere. The reference numeral 13 represents a vertically polarized ground wave having a vertical electric vector E and a horizontal magnetic vector H, at right angles thereto. In different localities the orientation of the ground

- wave vectors may vary somewhat from the orientation shown. The direction of propagation of the wave is at right angles to both vectors, as indicated by the arrow 15. It is well known that the plane of polarization contains the electric vector and is parallel to the direction of propagation. This plane may be rotated by the reflection from the ionosphere. The direction from which the sky wave approaches the receiving loop is different from that of the ground wave. The sky wave 17 is shown after reflection. The electric vector E is horizontal and the magnetic vector H is at right angles thereto and perpendicular to the direction of propagation, which is represented by the arrow 19. The rotation of the plane of polarization is not necessarily 90°, as illustrated. This angular rotation has been assumed for convenience of illustration.
- A loop antenna, such as that shown at 3, is known to have directional properties which depend on the polarization of the signals to be received. Reception is a maximum when the plane of the loop is parallel to the plane of polarization, and is a minimum when at right angles thereto. It is evident, therefore, that an orientation of the loop which effectually eliminates the ground wave signal 13, that is, an orientation with the loop plane perpendicular to the plane of polarization of the ground wave, does not eliminate the sky wave with a rotated plane of polarization. This effect is well known in directional compass work in which a false bearing is frequently obtained by reason of sky wave reception at the ground wave null point.
- By adjusting the loop antenna 3 about its vertical and horizontal axes to eliminate the ground wave signal during daylight hours, when there is no sky wave present, a true ground wave null is obtained, that is, the null is due entirely to the directional properties of the loop antenna with respect to the ground wave and not due to a particular phase relation between the ground and the sky wave signals. This adjustment cannot satisfactorily be accomplished at night for the reasons noted above. Consequently, having adjusted the loop antenna to eliminate the ground wave signal from a particular transmitter, night time reception is accomplished by utilizing only the sky wave signal, thus completely avoiding selective fading difficulties.
- To provide satisfactory reception during the day, it is necessary to provide another antenna or to minimize the directional properties of the loop. This may be accomplished, for example, by a switch 21 which is connected between the primary and secondary of the coupling transformer 7 through a capacitor 23. By unbalancing the system, in-phase currents, picked up by the lead-in 5, and the loop antenna 3, acting as a capacitive antenna, are coupled to the receiver. By operating the switch 21, ground wave or sky wave reception may be selected at will.
- While I have shown a loop antenna in connection with Fig. 1, any antenna having the desired directional properties may be employed. In Fig. 2, I have illustrated, by way of example, the use of a dipole antenna 25. The dipole antenna has this advantage over the loop antenna: it may be adjusted to eliminate the ground wave and yet still receive the sky wave even if the plane of polarization of the sky wave is the same as that of the ground wave. With the loop antenna, the planes of polarization of

the two waves must not be parallel, that is, one must have been rotated, or both waves will be eliminated together.

The pickup of the dipole is a minimum when the dipole conductors are parallel to the direction of propagation of the wave. Therefore, when the dipole is so adjusted as to eliminate the ground wave, the sky wave may be received, whether its plane of polarization has been rotated or not, because of its different direction of propagation. The pickup of the dipole is also a minimum when the dipole conductors are perpendicular to the plane of polarization of the wave. When so adjusted to eliminate the ground wave, the sky wave may be received only if its plane of polarization has been rotated.

In Fig. 2, the dipole antenna is coupled to the input of an amplifier 27 by means of transformer 7, as before. In-phase currents from the antenna and lead-in are coupled to the receiver 20 by means of a center tap connection from the primary of transformer 7 to the primary of a second transformer 28. The secondary of transformer 29 is coupled to the input of a second amplifier tube 31 whose plate is connected to the plate of amplifier tube 27. A switch 33 is connected so that it will short-circuit the primary of transformer 7. A switch 35 is connected so that it will short-circuit the primary of transformer 29. By opening switch 33 and closing switch 35, sky wave reception is obtained, while, in the reverse position, the antenna and lead-in function as a capacity antenna to receive the corresponding ground wave signals. For convenience, switches 33 and 35 may be operatively connected.

Electrical switching may be accomplished by applying suitable biasing voltages to the tubes 27 and 31. The biasing voltages are manually controlled by switches 43, 45 which, in one position, connect the cathode of tube 27 to ground and the cathode of tube 31 to a source of positive potential 49 for sky wave reception, and, in the other position, connect the positive bias from battery 47 to the cathode of tube 27, grounding the other cathode, for ground wave reception.

A modification of the directional antenna which is useful in simultaneously reducing the vertically polarized ground wave signals from several transmitters is shown in Fig. 3 in which a loop antenna 37 is adjustably mounted in an approximately horizontal plane. Such an antenna has the advantage of being equally non-responsive to vertically polarized signals from all directions in a horizontal plane. Consequently, man-made static, which is usually vertically polarized, as well as ground wave signals from nearby stations, may be reduced, while down coming sky waves may be received from all directions. Ground wave reception is provided by a separate antenna 39 which is connected to the receiver by a switch 41.

Since the ground wave signal is usually quite intense, in order to provide sufficient elimination it may be necessary to shield the lead-in conductors, the coupling device, and the receiver itself. The degree of success in shielding may be determined experimentally by the daytime adjustment, referred to above, in which the ground wave signal is eliminated from the receiver.

I have thus described a method for preventing selective fading due to interference between sky wave and ground wave signals which comprises adjusting a directional antenna to minimum response to the ground wave during a

time in which the sky wave is not present, and receiving only the sky wave signals when they are present, to obtain undistorted reception. I have illustrated several devices by means of which this method may be practiced.

5 I claim as my invention:

1. In a receiver for the reception of broadcast signals which includes an antenna system having a normally selective response characteristic and switching means for modifying said selective response, said system being normally adjusted to reject predetermined ground wave signals, the method of reducing selective fading due to interference between said predetermined 15 ground wave signals and corresponding sky wave signals which includes the steps of selectively rejecting ground wave signals and utilizing only the received sky wave signals during periods characterized by the presence of both ground 20 and sky wave signals, and modifying said selective characteristic to receive ground wave signals during periods in which said sky wave signals do not interfere with reception of said ground wave signals.
2. In a receiver for the reception of broadcast signals which includes an antenna system having a normally directive response characteristic and switching means for modifying said directive characteristic, said system being nor-

mally adjusted to reject predetermined ground wave signals, the method of reducing selective fading due to interference between said predetermined ground wave signals and corresponding sky wave signals which includes the steps of receiving and utilizing only sky wave signals during periods characterized by the presence of ground and sky wave signals, and modifying said directive characteristic to receive and utilize ground wave signals during periods in which said sky wave signals do not interfere with reception of said ground wave signals.

3. In a receiver for the reception of broadcast signals having a directional antenna system and switching means for modifying said directive characteristic, the method of reducing selective fading due to the simultaneous reception of ground and corresponding sky wave impulses, which includes the steps of adjusting said directional antenna system to reject predetermined ground wave signals during a period in which ground wave signals only are present, utilizing said directional system to receive sky wave signals only during periods characterized by the presence of sky wave signals, and modifying said system to receive ground wave signals during periods in which said sky wave signals do not cause selective fading.

CHARLES M. BURRILL.
